UNITED STATES PATENT OFFICE.

JACK A. PARTINGTON, OF SAN FRANCISCO, CALIFORNIA.

THEATER NOVELTY.

Application filed August 27, 1925. Serial No. 52,804.

This invention relates to theatrical novelties and particularly to a novel stage and mechanism cooperating therewith. Many theatrical acts require additional stage room, quick changes of additional stage settings, the provision of more than one scene simultaneously, the quick arrangement of such settings in a manner wherein the same will be most clearly observed by the audience, etc. In my Patent No. 1,563,782, dated December 1, 1925, I have disclosed one form of mechanism for serving these functions. The primary object of my present invention is to provide another and improved novel construction wherein these and other advantageous features are most efficiently obtained.

More specifically, my invention comprises a stage having an auxiliary portion or portions thereof movable from a position below to a position flush with the stage in a manner providing an enlarging of the stage when desired. The construction preferably comprises a pit at the front of the stage having an auxiliary stage therein and provided with means for moving the same to a position flush with the main stage, there also being a passage beneath the stage providing a communication from a rear auxiliary movable stage whereby a movable platform on the main stage can be moved from one auxiliary stage to the other beneath the main stage. It is an object of my invention to provide a mechanism of this type.

It is a further object of my invention to provide a novel railing and curtain carrying mechanism in connection with the pit and the movable auxiliary stage therein. These and other novel features of the invention will become apparent as this description proceeds.

In the accompanying drawings I have illustrated certain specific embodiments of my invention, but it will be understood that the invention can be otherwise embodied and that the drawings are not to be construed as defining or limiting the scope of the invention, the claims appended to this specification being relied upon for that purpose.

Referring to the figures of the drawings,

Fig. 1 is a fragmentary vertical sectional view through the stage portion of a theater showing the construction of my invention.

Fig. 2 is a fragmentary view thereof showing the parts in other positions.

Fig. 3 is an enlarged view thereof.

Fig. 4 is a plan view.

Referring more specifically to the drawings by reference characters, 1 indicates the base or foundation of a theater and 2 the main stage thereabove, the stage being supported on I-beams 3. The rear of the stage is provided with a section or portion 4 supported on hydraulic rams 5. These rams are adapted to move the portion 4 upwardly to a position flush with the stage 2 or to move the same downwardly to a position flush with the floor of the foundation 1.

A pit 6 is provided forwardly of the stage and an auxiliary stage 7 is supported on hydraulic rams 8 in this pit. These rams are adapted to move the auxiliary stage 7 upwardly to a position flush with the stage 2 or to move the same downwardly to a position flush with the floor of the foundation 1. As illustrated, a passage 9 is provided beneath the stage between the pit and the section 4. A steel fire curtain or door 10 is preferably provided between this passage and the pit, the curtain being adapted to be rolled upwardly on a roller 11 when desired.

One or more movable platforms are adapted to be used in connection with my novel stage. Preferably, I use a main platform 12 and a smaller platform 13. These platforms are mounted on wheels riding on tracks 14. The tracks extend across the main stage 2 and the floor of the passage 9 and cooperating tracks are provided on the stage sections 4 and 7. The platforms 12 and 13 are preferably power operated by electric motors as described in my said co-pending application, and the hydraulic rams are operated in the usual and well known manner.

A pair of long hydraulic rams 15 are provided within the foundation 1 beneath the stage 2. As illustrated in Fig. 1, these rams are adapted to elevate the platform 12 to a position above the main stage. In the lowermost position, as illustrated in Fig. 2, these rams are beneath the surface of the floor in the passage 9 whereby the same do not obstruct the movement of the platforms 12 and 13 therethrough. It will also be noted that the platform 13 is sufficiently narrow to pass between the rams 15 so that when the platform 12 is elevated as shown

in Fig. 1, the platform 13 can pass thereunder.

A railing and curtain supporting frame 16 is provided forwardly of the pit 6. This 5 frame is carried for vertical movement on a pair of vertical tracks 17 adjacent the front of the stage respectively at the opposite sides of the pit. As illustrated, each of these tracks is an I-beam and the frame carrying 10 rollers 18 engage within the beams. Counter-weights 19 hung on cords 20 extending over pulleys 21 counterbalance the weight of the frame. A curtain 22 is hung from the frame, the curtain being received within a 15 pit 23 when the frame is in its down position. Power means (not illustrated) is adapted to raise and lower the frame and curtain on the tracks 7.

The curtain preferably comprises two half 20 portions overlapping each other at the center when the curtain is closed. These curtains are mounted on rollers 24 riding on a horizontal track 25 extending around the inside of the railing or frame 16. Cords are 25 attached to the curtains and operate in a well known manner for moving the two curtain halves simultaneously in opposite directions to open or close the curtains when desired, the rollers 24 carrying the curtains 30 along on the track 25.

A novel form of foot-light device 26 is provided at the forward edge of the stage 2 adjacent the auxiliary stage 7. This device is pivoted at 27 and movable thereabout to 35 two positions. When the auxiliary stage 7 is not being used flush with the stage 2, the device is pivoted to the position illustrated in Fig. 2, wherein the same acts as a foot-light reflector. When using the auxiliary 40 stage 7 flush with the stage 2, the device is pivoted to the position illustrated in Fig. 4, wherein the flat surface 28 bridges the gap between the auxiliary and main stages.

A main orchestra pit can be provided at 45 29 forwardly of the pit 6 if desired, a railing 30 being provided between such pit and the seating portion of the theater. It may also be desired at times to use an extra platform on the tracks 14. For this purpose I provide 50 a chamber 31 beneath the pit 29 for storing an extra platform 32. This platform can be rolled out onto the auxiliary stage 7 whenever its use is desired.

It is believed that the construction and 55 operation of my improvements will be clear without further description herein. The novel construction provides means for making various combinations and arrangements adapted to the acts or effects it is desired to 60 produce. A scene can be prepared on either auxiliary stage 4 or 7, or on the platforms 12 and 13 beneath the main stage, and then elevated to the main stage either at the front or rear thereof. If elevated at the front of 65 the stage, the platform can thereafter be

moved over the stage to the section 4 and lowered to the passage 9 while another act is being brought upward on the auxiliary platform 7. It will also be noted that the frame 16 provides an orchestra railing about the 70 orchestra or other act on the stage 7 when desired, and that the elevating of such rail hides the entire stage behind the curtain 22. A curtain 33 is also provided on the platform 12 for use when the same is elevated as 75 shown in Fig. 1. Further description of the possibilities of my invention is believed to be unnecessary since it is obvious that many and various novel settings are possible.

Having thus described my invention, what 80 I claim and desire to secure by Letters Patent is—

1. A theater novelty comprising the combination of a stage, front and rear portions thereof being movable to positions flush with 85 the stage and below the level thereof, the stage intermediate the said portions being stationary, means for elevating and lowering such portions to such positions, and means providing a communicating passage 90 below the stage between such portions.

2. A theater novelty comprising the combination of a stage, front and rear portions thereof being movable to positions flush with the stage and below the level thereof, the 95 stage intermediate the said portions being stationary, means for elevating and lowering such portions to such positions, a platform movable over the stage and adapted to be carried on the said movable portions, and means providing a communicating passage 100 below the stage between such portions whereby the platform can be moved from one portion to the other beneath the stage.

3. A theater novelty comprising the combination of a stage, front and rear portions thereof being movable to positions flush with the stage and below the level thereof, the stage intermediate the said portions being 105 stationary, means for elevating and lowering such portions to such positions, a track extending over the stage including the front and rear portions, a platform riding on the track, means providing a communicating passage below the stage between the said 110 portions, a track between such portions beneath the stage, and power means for moving the platform.

4. A theater novelty comprising the combination of a stage, front and rear portions thereof being movable to positions flush with the stage and below the level thereof, means for elevating and lowering such portions to such positions, a platform movable over the stage and adapted to be carried on the said 115 movable portions, means providing a communicating passage below the stage between such portions whereby the platform can be moved from one portion to the other beneath the stage, and means for elevating the plat- 120

form above the stage intermediate the said portions.

5. A theatrical novelty comprising the combination of a stage, front and rear portions thereof being movable to positions flush with the stage and below the level thereof, hydraulic rams for elevating and lowering such portions to such positions, a platform movable over the stage and adapted to be carried on the said movable portions, means providing a communicating passage below the stage between such portions whereby the platform can be moved from one portion to the other beneath the stage, and hydraulic rams adapted to extend up through the stage and elevate the platform above the stage intermediate the said portions.

6. A theatrical novelty comprising the combination of a stage, means providing a pit at the front of the stage, an auxiliary stage in the pit, means for elevating the auxiliary stage to a position flush with the stage, and pivotally mounted means at the front of the main stage adapted in one pivoted position to provide a foot-light reflector and in another pivoted position to provide a bridge for gapping the space between the stage and the auxiliary stage.

30 7. A theatrical novelty comprising the

combination of a stage, means providing a pit at the front of the stage, an auxiliary stage in the pit, means for elevating the auxiliary stage to a position flush with the stage, curtain supporting means forwardly 35 of the pit, a curtain hung therefrom, and a pair of vertical tracks carrying the curtain supporting means in a manner permitting the curtain to be elevated and lowered to positions above and below the stage level 40 to cooperate with the auxiliary stage in its different positions.

8. A theatrical novelty comprising the combination of a stage, means providing a pit at the front of the stage, an auxiliary 45 stage in the pit, means for elevating the auxiliary stage to a position flush with the stage, a pair of vertical tracks adjacent the forward portion of the stage, a railing extending about the front portion of the pit 50 and movably carried on the tracks, a horizontal track on the railing, a flexible curtain, means carrying the flexible curtain on the horizontal tracks, and means for elevating and lowering the tracks and curtain 55 to positions above and below the stage level to cooperate with the auxiliary stage in its different positions.

JACK A. PARTINGTON.
